(57) CLAIM

The ornamental design of an upper handle of a floor care appliance, as shown and described.

DESCRIPTION

FIG. 1 is a front perspective view of an upper handle of a floor care appliance showing our new design;

FIG. 2 is a front view thereof;

FIG. 3 is a left side view thereof;

FIG. 4 is a right side view thereof;

FIG. 5 is a rear view thereof; and,

FIG. 6 is a top view thereof.

The portions shown in dashed lines are shown for illustrative purposes only and form no part of the claimed design.
